Patented Sept. 8, 1925.

UNITED STATES PATENT OFFICE.

JOEL FRANK BARNETT, OF ALVA, KENTUCKY.

MINE TIE AND RAIL CLAMP.

Application filed March 7, 1925. Serial No. 13,903.

To all whom it may concern:

Be it known that I, JOEL FRANK BARNETT, a citizen of the United States, residing at Alva, in the county of Harlan and State of Kentucky, have invented certain new and useful Improvements in Mine Ties and Rail Clamps; and I do hereby declare the following to be a full, clear, and exact description of the invention, such as will enable others skilled in the art to which it appertains to make and use the same:

This invention relates to railway ties and more particularly to ties for mine railways.

The invention has for one of its objects the provision of a novel, simple and inexpensive tie by means of which mine rails may be firmly supported in vertical or horizontal position and by means of which vertically and horizontally positioned rails may be firmly connected together and supported in their respective positions.

With the above and other objects in view, the invention consists of the construction, combination and arrangement of parts hereinafter fully described and claimed, and illustrated in the accompanying drawing, wherein:

Figure 1 is a view in side elevation of a tie constructed in accordance with my invention, the tie being illustrated as supporting two mine rails in upright position.

Figure 2 is a top plan view of the tie supporting mine rails in upright position.

Figure 3 is a view partly in elevation and partly in vertical section of one end of the tie.

Figure 4 is a sectional view taken on the horizontal planes indicated by the line 4—4 of Figure 3.

Figure 5 is a view similar to Figure 3 illustrating the manner in which the tie is adapted to support a mine rail in horizontal position.

Figure 6 is a sectional view taken on the horizontal planes indicated by the line 6—6 of Figure 5.

Figure 7 is a view similar to Figures 3 and 5 illustrating the manner in which the tie is adapted to connect and support vertically and horizontally positioned mine rails, and

Figure 8 is a sectional view taken on the horizontal planes indicated by the line 8—8 of Figure 7.

Corresponding and like parts are referred

to in the following description, and designated in the several views of the accompanying drawing, by similar reference characters.

The tie 5 is made of metal and the main body portion thereof is comparatively thin while its terminal portions are of considerable thickness to provide rail seats 6. Jaws 7 are formed integrally with the ends of the tie 5 and overlie the rail seats 6. In practice, the rails 8, when they are to be supported in vertical position, rest upon the seats 6 with their outer base flanges beneath the jaws 7, the jaws contacting with said base flanges and the webs of the rails. Clamps 9 are secured to the tie 5 inwardly of the rail seats 6, and each comprises a body portion 10, a jaw 11 extending longitudinally from one end of the body, and an arm 12 extending upwardly from the other end of the body and provided at its upper end with a downturned hook 13. The jaws 11 contact with the inner base flanges and the webs of the rails 8 and cooperate with the jaws 7 to firmly secure the rails to the tie 5. The bodies 10 are provided with longitudinally extending slots 14 each of which is provided in one edge with a recess 15 and in the opposite edge with recesses 16 and 17. Bolts 18 extending through the slots 14 and received by the notches 15 secure the clamps 9 to the tie 5. The bolts 18 pass freely through the slots 14 and have threaded engagement with the tie 5, and washers 19 are positioned between the clamps 9 and the heads of the bolts 18.

The jaws 11 of the clamps 9 are employed when it is desired to secure vertically arranged rails to the tie 5. The arms 12 and hooks 13 of the clamps 9 are employed when it is desired to secure horizontally arranged rails to the tie 5, or when it is desired to secure the contiguous portions of vertically and horizontally arranged rails to the tie.

When horizontally arranged rails are to be secured to the tie 5, they are positioned upon the tie with their heads in contact with the rail seats 6 and the inner ends of the jaws 7 and with the lower edges of their bases in contact with the tie inwardly beyond the rail seats, as shown in Figures 5 and 6 wherein the rail is designated 8^a. The clamps 9 are reversed upon the tie 5 so that the arms 12 thereof will contact with the vertical side of the bases of the rails 8^a and the hooks 13 engage over the upper edges of 110

the bases. The clamps are secured in position by entering the bolts 18 in the notches 17. When it is desired to secure the contiguous ends of vertically and horizontally arranged rails to the tie 5, the vertically arranged rails 8^b are positioned upon the rail seats 6 with the hooks 7 overlying and contacting with the outer base flanges thereof, and the horizontally arranged rails 8^c 10 are positioned upon the tie with their heads contacting with the inner sides of the webs of the rails 8^b and with the lower edges of their bases in contact with the tie, as shown in Figures 7 and 8. The arms 12 contact 15 with the vertical sides of the bases of the horizontally arranged rails 8^c and the hooks 13 engage over the upper edges of said bases. In this instance, the clamps 9 are secured in place by entering bolts 18 in the notches 16. 20 The ties may be spiked to the ground or they may be spiked to wood ties, and to permit of this being done, the ties are provided with spike receiving openings 20.

It should be understood that the drawing 25 is merely illustrative and does not pretend to give exact proportions. Furthermore, the said drawing is illustrative of a preferred construction, it being my expectation that various changes and modifications may be 30 made without departing from the spirit and scope of the invention.

What is claimed is:—

1. A tie provided at its ends with rail seats spaced above the top side thereof, outer jaws formed integrally with the ends of the tie and overlying the rail seats, clamps secured to the tie below the rail seats and provided with upwardly extending jaws, and means reversibly securing the clamps to the tie. 40

2. A tie having ends of increased thickness to provide rail seats, jaws formed integrally with the ends of the tie and overlying the rail seats, clamps provided with jaws, and arms provided with hooks, said 45 clamps being provided with slots having notches in the opposite walls thereof, and a bolt passing through the slots engaging the tie and entering one of said notches.

3. A rail clamp comprising a body portion 50 provided at one end with a longitudinally extending jaw and at its opposite end with an upstanding arm terminally provided with a hook.

4. A rail clamp comprising a body portion 55 provided with an elongated slot having notches in its opposite sides, a longitudinally extending jaw at one end of the body, and an upstanding arm at the other end of the body and provided with a downturned hook. 60

In testimony whereof I affix my signature:
J. FRANK BARNETT.
